UNITED STATES PATENT OFFICE.

HUGH S. ALEXANDER, OF ST. PAUL, MINNESOTA.

CHART-PRINTING MACHINE.

1,123,062.

Specification of Letters Patent. Patented Dec. 29, 1914.

Application filed April 28, 1913. Serial No. 764,108.

To all whom it may concern:

Be it known that I, HUGH S. ALEXANDER, a citizen of the United States, residing at St. Paul, in the county of Ramsey and State of Minnesota, have invented certain new and useful Improvements in Chart-Printing Machines, of which the following is a specification.

The object of my invention is to provide a machine adapted to print suitable indicia on large work, such as charts, and to combine with this machine a hinged or removable top which may be used as a drawing table when in closed position; and with these and other objects in view, my invention consists in the parts and combination of parts as will be hereinafter more fully set forth.

In the drawings: Figure 1 is a top plan view of a chart printing machine embodying my invention, the top being removed. Fig. 2 is a longitudinal vertical section of the machine. Fig. 3 is a transverse section on the line 3—3, Fig. 1. Fig. 4 is a detail bottom plan view showing the inking rolls and associated parts. Fig. 5 is a perspective view of the type carrying frame and associated parts. Fig. 6 is an enlarged sectional view on the line 6—6, Fig. 3, parts being in elevation. Fig. 7 is a detail enlarged sectional view on the line 7—7, Fig. 1, looking in the direction of the arrow. Fig. 8 is an enlarged detail view of the escapement mechanism for the carriage. Fig. 9 is a vertical sectional view of the machine with the top closed, parts being broken away.

The reference numeral 1 designates the frame of a drawing table provided with a top 2 hinged at one end thereof. 3 are cross members secured in the frame on which is journaled the platen 4.

5 is a rod suitably secured in the frame and extending longitudinally thereof on which is detachably mounted a carriage 6, to which is connected a cord 7 and a weight 8, said cord passing over a sheave 9.

10 is a rack bar secured to the frame 1 with which the dog 11 is adapted to engage, said dog being held normally into engagement with said rack by means of the spring 13.

14 is a rod suitably mounted on the car-

riage in the cleats 15 and 16, the dog 11 being secured to one end of said rod.

17 is a spring coiled around the rod 14, one end of which is seated on the cleat 15, while the other end is seated against the under face of the knob 18 on the rod, whereby the dog 11 is held normally in engagement with the rack bar. Whenever it is desired to disengage the dog from the rack bar, the rod 14 is pressed outwardly carrying with it the dog and the carriage 6 is then free to move along the rod 5.

The carriage 6 is provided with a forwardly extending substantially U-shaped member 19 in the top edges of which are formed suitable stops 20.

21 is a member projecting from one side on which is arranged suitable indicia of the characters that may be printed, said indicia bearing a definite relation to the stops 20.

22 is a bow spring secured to and depending from the under face of the one end of the member 19 and adapted to bear upon the top edge of one side of the frame as more clearly shown in Fig. 7.

The frame is provided with a groove 23 which is engaged by a catch 24 depending from the member 19 of the carriage, whereby the vertical motion of the carriage is properly limited and the vibration on the bow spring 22 damped.

The carriage member 19 is provided with a longitudinally extending groove 25 on each side in which slides a type carrying frame consisting of side rods 26 coupled at each end by means of the plates 27 and 28, said plates being perforated to provide a bearing for the journals 29 of the type carrying member 30.

The coil spring 31 is interposed between the plate 28 and the adjacent end of the type carrying member 30, whereby the locking pin 32 is held normally in engagement with one of the notches 33 formed on the band 34, whereby the type carrying member 30 is locked firmly in its adjusted positions.

The type carrying member 30 is provided with a series of type 31^a, see Fig. 6, which may be varied according to the work the machine is designed to do.

35 are ink rolls mounted on the member 19 and carried by spring arms 36.

37 are shields arranged under the ink

rolls and provided with forwardly extending tongues 38 which are spaced immediately over the printing center of the platen 4 as clearly shown in Fig. 3.

5 The frame 26 is provided with a locking bar 39 pivoted to the plate 28, said bar being constructed to engage the stops 20, thereby locking the frame in an adjusted position in the carriage member 19.

10 Of course it will be understood that the platen 4 may be provided with any of the well known forms of platen operating mechanism, such as are used on typewriters.

15 The frame is supported upon suitable legs or supports 40.

In operating the machine the chart 41 is secured to the platen by means of thumb tacks 42 or any other suitable fastening means and the point to be printed on the 20 chart is brought directly under the space between the projections 38; the type carrying member 30 is then revolved by means of the member 32 to bring the proper series of characters on the under face of the member 25 30, whereupon the frame 26 is moved in the carriage in the direction of line spacing until the locking bar is opposite the notch representing the character to be printed, whereupon the bar 39 is depressed into the notch, 35 thus locking the type carrying member 30 in proper position for printing the desired character, and by continued depression of the bar 39 the free end of the carriage is depressed against the tension of the bow spring 22 so as to bring the type 31 into contact with the chart for the purpose of printing thereon. In this connection it will be observed that the bow spring 22 maintains the carriage and the type normally 40 spaced from the platen. The carriage 6 is then moved to the right one or more spaces by depressing and releasing the left end of the dog 11. This operation is repeated until a line is completed.

45 It will be noted that the carriage is movable only in the direction of letter spacing, whereas the type carrying member 30 is movable in the direction of line spacing.

I claim:

50 1. In a chart printing machine, the combination with a platen, of a carriage, movable in the direction of letter spacing, a frame mounted on said carriage and slideable thereon in the direction of line spacing, a locking bar carried by said frame, stops 55 on the carriage constructed to be engaged by said bar, a type carrying member journaled in said frame, a lock for said member, one part of which is carried by the said member and the other by said frame, and a coiled spring, one end of which is seated on the said member while the other end is seated on the frame, whereby the parts of said lock are held normally interlocked.

65 2. In a chart printing machine, the com-

bination with a frame, of a platen mounted in said frame, a type carriage swingingly mounted at one end in said frame, a bow spring depending from the other end of the carriage and constructed to rest on the top 70 of said frame to provide clearance between the platen and the type on said carriage.

3. In a chart printing machine, the combination with a frame, of a platen revolvably mounted in said frame, a rod in said frame, 75 a carriage slidably mounted on said rod, means to move said carriage step by step in the direction of letter spacing and means locking said carriage in an adjusted position, stops on said carriage, indicia for said 80 stops, a frame slidably mounted on said carriage and movable in the direction of line spacing, a locking bar carried by said sliding frame and constructed to engage said stops, a type carrying member revolvably 85 mounted in said frame, ink rolls carried by the carriage, a bow spring depending from the free end of the carriage and positioned to engage the top of the first named frame to provide, normally, a clearance between 90 the platen and type member.

4. In a chart printer, the combination with a roller platen, of a carriage movable longitudinally of said roller platen, and extending transversely over said roller platen, 95 an indicia of the characters to be printed attached to said carriage, a rectangular frame slidably mounted in said carriage and adapted to slide in a direction at right angles to the said roller platen, a type bar revolvably mounted in said rectangular frame and a member hinged at one end to said rectangular framework and provided with a transverse handle bar at its free end, said handle bar arranged to engage said stops 100 and to extend over the aforesaid indicia.

5. In a chart printer, a type carrying frame, comprising a rectangular frame, the sides of which constitute slides, adapted to be mounted in a slideway, a type carrying member journaled in said frame and extending longitudinally thereof, a locking bar pivotally mounted on said frame, a band mounted in said frame, notches in said band, and a locking pin carried by said type carrying member adapted to engage said 110 notches and hold said member in an adjusted position.

6. In a chart printer, the combination with a carriage comprising side members 120 having a series of notches in their upper edges, indicia arranged along one side member and spaced relatively to said notches and slideways in the inner face of said members, of a rectangular type carrying frame, the 125 sides of which constitute slides adapted to be slidably mounted in said slideways, a type carrying member journaled in the type carrying frame and extending longitudinally therein, type on said member spaced 130

relatively with said notches and indicia, a locking bar pivotally mounted on said type carrying frame and adapted to interlock with said notches to hold the type carrying frame in an adjusted position.

7. In a chart printer, the combination with a carriage comprising side members having a series of notches in their upper edges, indicia arranged along one side member and spaced relatively to said notches and slideways in the inner face of said side members, of a rectangular type carrying frame, the sides of which constitute slides adapted to be slidably mounted in said slide-
ways, a type carrying member journaled in the type carrying frame and extending longitudinally therein, type on said member

spaced relatively with said notches and indicia, a locking bar pivotally mounted on said type carrying frame and adapted to interlock with said notches to hold the type carrying frame in an adjusted position, a band mounted on said carriage, notches in said band, and a locking pin secured to said type carrying frame and adapted to engage said notches and hold the type carrying frame in an adjusted position.

The foregoing specification signed at St. Paul, Minn. this 21st day of April, 1913.

HUGH S. ALEXANDER.
